[57] CLAIM

The ornamental design for a cigarette extinguisher, as shown and described.

DESCRIPTION

FIG. 1 is a perspective view of a cigarette extinguisher showing my new design;

FIG. 2 is a plan view of the top end thereof;

FIG. 3 is a plan view of the bottom end thereof;

FIG. 4 is an elevational view of the front thereof; the rear elevational view being a mirror image thereof; and,

FIG. 5 is an elevational view of one side thereof, the other side elevational view being a mirror image thereof.
